(57) **CLAIM**

The ornamental design for a footwear sole, as shown and described.

DESCRIPTION

FIG. 1 is a perspective view of a footwear sole, embodying the new design;

FIG. 2 is a bottom view thereof;

FIG. 3 is a right side view thereof;

FIG. 4 is a left side view thereof;

FIG. 5 is a front view thereof; and,

FIG. 6 is a rear view thereof.

The figures show features in broken lines that form no part of the claimed design. Further, the broken lines immediately adjacent to the solid line portions form the boundary of the claimed design, with the broken lines forming no part of the claimed design.

1 Claim, 5 Drawing Sheets
